UNITED STATES PATENT OFFICE.

HORRY C. BUNNELL, OF WESTPORT, NEW YORK.

CONVERTIBLE CHAIR.

1,423,995.

Specification of Letters Patent. Patented July 25, 1922.

Application filed April 14, 1922. Serial No. 552,542.

To all whom it may concern:

Be it known that I, HORRY C. BUNNELL, a citizen of the United States, residing at Westport, in the county of Essex and the State of New York, have invented certain new and useful Improvements in Convertible Chairs, of which the following is a specification.

This invention is an improvement on the bungalow chair for which Letters Patent have been granted to me bearing No. 794,777, and to which reference is had.

The object of the present invention is to make the said chair convertible at will into a rocking chair.

The invention consists of the novel features of construction hereinafter described, pointed out in the claims and shown in the accompanying drawing in which:—

20 Figure 1 is a side elevation, the rockers being lifted into inoperative position.

Figure 2 is a side elevation showing the rockers lowered into operative position.

Figure 3 is a rear elevation the parts being shown in the same position as in Figure 2.

In the drawing 1 designates my chair which has a solid back piece and solid side supporting members 2, front legs 3 and foot rest 4, all as shown and fully described in the patent above referred to.

The improvement that I have added to this chair is as follows: Rockers 5 are pivotally connected to the supporting legs 3 in any desired manner, said rockers being spaced from and parallel to the side members 2, which as shown in Figure 3 are rearwardly converging. These rockers to the rear of the chair are connected by a rod 6. Across the back of the chair is a cross piece 7, which supports the rear portions of the chair arms. A bar 8 is pivoted to the intermediate portion of the rod 6 and is notched as at 9 to engage the upper edge of the cross piece 7, and the free end of the bar is also bevelled to fit under said cross piece

and against the chair back, as shown in Figures 2 and 3. A hook 10 is adapted to engage staples 11 placed respectively on opposite sides of the bar 8.

It will be noted that the staple 11 on the rear or outer face of the bar is in a higher plane than the staple on the inner face of the bar. When the hook 10 is engaged with this last, lower positioned, staple the notch 9 is in engagement with the upper edge of the cross piece and the rockers are lifted above the lower edge of the side members 2 so that the chair rests solidly upon the floor. But when the bar 8 is placed beneath the cross piece, in which position the hook 10 engages the outer and higher staple, the rockers are forced downwardly below the plane of the bottom of the side members 2, and the chair is converted into one of the rocker type.

The simplicity and advantages of the construction employed will be obvious.

What I claim is:—

1. The combination with a chair, of rockers pivoted to said chair at their forward ends, a cross piece at the rear of the chair, a rod connecting the rear portion of the rockers, a bar pivotally carried by said rod, the bar being notched to engage the upper edge of the cross piece and beveled to fit under said cross piece, and means for locking the bar in place.

2. The combination with a chair having side member normally resting on the ground and having forward legs, of rockers pivotally connected to said legs and extending parallel but spaced from the side members, a cross piece at the back of the chair, a rod connecting the rear portion of the rockers, a bar pivotally carried intermediate the ends of the rod, and means carried by the bar and by the said cross piece for locking the bar in adjusted position, as and for the purpose set forth.

In testimony whereof I affix my signature.

HORRY C. BUNNELL.
